CLEAT FOR BOATS

William R. Tritt, 3608 Lake St., Newport Beach, Calif.

Filed Oct. 27, 1959, Ser. No. 58,079

Term of patent 14 years

(Cl. D54—11)

Fig. 2.

Fig. 3.

Fig. 4.

Fig. 5.

Fig. 6.

Fig. 1 is a side elevation of a cleat for boats showing my new design;

Fig. 2 is a top plan view thereof;

Fig. 3 is an end view thereof looking toward the left end of the cleat as shown in Fig. 1;

Fig. 4 is an end view thereof looking toward the right end of the cleat as shown in Fig. 1;

Fig. 5 is a sectional view taken on the line 5—5 of Fig. 1; and

Fig. 6 is a sectional view taken on the line 6—6 of Fig. 1.

I claim:

The ornamental design for a cleat for boats, as shown.
